(No Model.)

H. C. DERR.
RAILWAY SWITCH.

No. 564,916.

Patented July 28, 1896.

UNITED STATES PATENT OFFICE.

HEISTER C. DERR, OF NESCOPECK, PENNSYLVANIA, ASSIGNOR OF ONE-HALF TO BOYD R. YETTER, OF MAINVILLE, PENNSYLVANIA.

RAILWAY-SWITCH.

SPECIFICATION forming part of Letters Patent No. 564,916, dated July 28, 1896.

Application filed September 6, 1895. Serial No. 561,664. (No model.)

To all whom it may concern:

Be it known that I, HEISTER C. DERR, a citizen of the United States, residing at Nescopeck, in the county of Luzerne and State of Pennsylvania, have invented certain new and useful Improvements in Railway-Switches, of which the following is a specification, reference being had therein to the accompanying drawings.

10 In the drawings, Figure 1 is a plan view of a portion of a railway-track, showing my improved mechanism; Fig. 2, a vertical longitudinal section through the channeled shoe or block; Fig. 3, a transverse section through 15 the same; Figs. 4 and 5, detail vertical sections through the switch-stand devices; Fig. 6, a detail view in outline of a locomotive, showing more particularly the manner of shifting the operating-bar carried by the locomotive; and Fig. 7, a detail plan view of 20 the operating-bar and the connected parts.

This invention is designed to provide improved and extremely simple devices whereby the operator may open the switch automatically from the cab of the locomotive as the 25 same approaches the switch, or by manual power through the medium of the usual switch-stand alongside the track, the devices being adapted to lock the switch-rails in either 30 position, as and for the purposes herein set forth.

Referring to the drawings by numerals, 1 is the shoe, which is securely fastened down to the ties a suitable distance ahead of the 35 switch-rails, and which is channeled longitudinally at 2, the forward end of the channel being suitably flared to facilitate the entrance of the operating-bar carried by the locomotive. Pivoted on the shoe at one side of the 40 channel is an angle-lever 3, whose longer arm works in horizontal slots 4 in the sides of the shoe and extends (when the switch is closed) across the channel 2. The shorter arm of this angle-lever is connected by a rod 5 to another 45 angle-lever 6, pivoted to one of the ties near the forward ends of the switch-rails, the opposite arm of this latter angle-lever being connected by a link 7 to the bar 8, carrying the switch-rails. By this arrangement of levers 50 and rods it will be seen that by throwing the free arm of the angle-lever 3 backward or for-

ward the switch-rails may be closed or opened as may be desired. The operating bar or tappet 9 is carried by the locomotive, preferably on the under side of the cow-catcher. The 55 tappet is pivoted on a rod 10, whereby it may be turned down or up at the will of the engineer in the locomotive-cab, suitable links and levers being connected to the upper end of the tappet and being within convenient reach of 60 the engineer.

It will be observed that when the tappet is turned down, as shown in Fig. 6, it will pass into the widened mouth of the channel and strike against the transverse arm of the angle-lever 3 and open the switch.

As is evident, the same devices may be duplicated and placed between the rails of the siding, so that after a train has passed onto a siding the switch-rails may be automatically 70 closed again without stopping the train. The mouth of the shoe is kept normally closed by means of a plate 11, which is pivoted at its rear end at the widened part of the channel and which inclines upwardly and forwardly 75 and terminates just in the rear of the free arm of the angle-lever 3, said plate being kept normally pressed upward against flanges 12, carried by the shoe, by means of a strong spring 13, surrounding its pivot 14. The object of this spring-actuated guard is not only 80 to prevent the accumulation of obstructive substances in the mouth of the channel, but also to prevent any chains or other parts that may be dangling from passing trains striking 85 the angle-lever and operating the switch-rails. The spring 13 will of course be sufficiently strong to prevent any ordinary pressure upon the guard from depressing it, but will not be so strong as to prevent the operating-tappet from readily depressing it as the 90 train passes along.

To provide for shifting the switch-rails from the switch-stand in the usual manner and to insure the locking of the switch-rails, 95 whether they be open or closed, the switch-stand devices are constructed in a peculiar manner. One end of the bar 8 is connected by means of a rod 15 to a horizontal arm carried by the lower part 16 of a two-part clutch 100 carried by the vertical shaft 17 of the switch-stand. The part 16 of the clutch is mounted

loosely on the shaft 17, so as to turn thereon, but the upper part 18 of the clutch is secured on the shaft by means of a spline and feather, or any other suitable way, whereby it shall 5 rotate with the shaft, but may slide endwise independently of the same. The adjacent ends of the clutch-sections are provided with interlocking teeth, which are inclined equally in opposite directions, and the upper sliding 10 part of the clutch is kept normally pressed against the lower part by means of a strong coil-spring 19. The shaft 17 of the switch-stand is operated in the usual manner by means of a lever 20, which is adapted to engage 15 in notches 21, formed in the head of the switch-stand and be thereby locked in position against rotation.

It will be observed that the switch-rails may be shifted by lifting the lever out of the 20 notches and rotating it in either direction, the spring 19 being strong enough to prevent the parts of the clutch separating under the comparatively slight exertion required to shift the rails through the medium of the switch-stand devices. It will be observed, however, 25 that when the rails are shifted from the locomotive, the peculiar shape of the clutch-teeth will permit the lower part of the clutch to be turned sufficiently in either direction to permit the rails to move the required distance, the upper part of the clutch yielding upwardly as the lower part rotates. Thus it will be seen that the rails will always be locked and that they may be shifted manually from the 30 switch-stand or automatically from the locomotive, notwithstanding the fact that they are locked in place by the switch-stand devices.

As is evident, an operating-tappet may be mounted on the caboose, if desired, in order

to permit the switch to be closed automatically after it has passed onto the siding.

Having thus fully described my invention, what I claim is—

1. The combination of a main track, side track and switch-rails, a shoe channeled, a 45 guard-plate pivoted in the mouth of the channel and normally pressed up to close the same a lever extending across the channel behind the guard-plate, and mechanism connecting said lever to the switch-rails, as and for the 50 purposes set forth.

2. In combination with a main track and side track and switch-rails, of a shoe channeled longitudinally, a guard-plate supported in the mouth of said channel and normally 55 pressed up to close the same, devices for shifting the switch-rails, and a movable part in the channel behind the guard-plate and connected to said shifting devices, substantially as described.

3. In combination with a main track and side track and switch-rails, of a channeled shoe having a flanged mouth at its forward 65 end, a guard-plate pivoted in the lower end of said mouth and inclining upwardly therein and bearing against said flanges, a spring normally pressing said guard-plate up to close the mouth, and devices for shifting the switch-rails, a part of said devices being located in the channel behind the guard-plate, 70 substantially as described.

In testimony whereof I affix my signature in presence of two witnesses.

HEISTER C. DERR.

Witnesses:

CHARLES C. EVANS,
A. M. HUGHES.
